UNITED STATES PATENT OFFICE

FRANK W. KNOTT, OF DETROIT, MICHIGAN, ASSIGNOR TO KNOTT & GARILLUS COMPANY,
OF DETROIT, MICHIGAN, A CORPORATION OF MICHIGAN

MASSAGING-MACHINE CABINET

Application filed May 28, 1929. Serial No. 366,544.

My device relates to a special cabinet for retaining a vibrating massaging machine, which is more fully set forth in a former Patent, No. 1,693,300.

5 The object of my invention is to produce a special cabinet for massaging machines adapted for permanent installation and storing the devices therein.

Another object is to produce a cabinet for 10 a massaging machine, so designed and constructed that the machine may be positioned and retained therein for operating same, yet easily detached and folded within the cabinet for storing.

15 A further object is to produce a special cabinet so designed that when the machine is placed in the operating position, the cabinet members provide rigid bracing supports therefor and without any floor or wall adjustments being made.

20 A still further object of my invention is to provide an enclosing cabinet for massaging machines, having a neat and presentable appearance, constructed of a design capable of being matched with other room furniture and completely concealing and protecting the machine when not in use.

Another object is to produce an ornamental cabinet as a part of room furniture equipment that will allow the enclosed machine to be easily and efficiently operated from its position within the enclosing cabinet and that can be manufactured at a very reasonable cost.

25 These several objects are attained in the preferred form by the construction and arrangement of parts more fully hereinafter set forth.

Similar parts on all drawings are marked 30 by similar numerals or letters.

Fig. 1 is a front view of the cabinet, showing the door panel in its closed position.

Fig. 2 is a side view of the cabinet, showing the door panel partially opened, and 35 means for attaching the same to the cabinet base.

Fig. 3 is a front view of the cabinet, with the door panel removed, showing the interior structure and supporting frames within the cabinet, having a massaging machine head

mounted thereon, all folded within the cabinet, to a vertical position for storing the massaging machine therein.

Fig. 4 is also a front view of the cabinet, with the panel door in its open position, 55 showing the interior construction and frame work, and the massaging machine mounted therein, turned to a horizontal position as required for operating the machine.

Fig. 5 is a vertical sectional view taken on line 5—5 of Fig. 3 through the center line 60 of the cabinet, showing the supporting frame and pivoted base with the massaging machine mounted thereon, as folded to the vertical position within the cabinet, and the front 65 door panel closed.

Fig. 6 is also a vertical sectional view taken on line 6—6 of Fig. 4 along the center line 70 thereof, showing the mechanical structure, but with the pivoted base plate and attached massaging machine and operating motor turned to the horizontal position, as required when the device is being operated, and also shows the means for operating and retaining the base in the horizontal position. 75

Fig. 7 is a sectional view taken on line 7—7 of Fig. 2, showing the rear section of the supporting frame and means for engaging and retaining the pivoted base plate in a horizontal position. 80

Fig. 8 is a horizontal sectional view taken on line 8—8 of Fig. 4, showing the metal supporting frame and pivoted base plate in its horizontal position, but with the massaging machine head and operating motor 85 completely removed therefrom, and also showing the panel door in the open position and means for rigidly bracing the cabinet when the massaging machine is in operation.

I will now describe more fully the detailed 90 construction of my cabinet, referring to the drawings and the marks thereon.

In general, my device comprises a rectangular-shaped cabinet, preferably formed of wood material, having one side panel pivoted 95 thereto at the bottom, capable of unfolding to a position parallel with the floor and resting thereon. Within the cabinet is mounted a rigid supporting frame, provided with a pivotally attached base capable of being ad- 100

justed to either a vertical or a horizontal position for receiving and retaining a massaging machine fixedly attached thereon.

I have shown my cabinet structure in combination with a massaging machine and operating motor, more specifically set forth in my former patent heretofore mentioned, for the purpose of more clearly illustrating the use and application of this invention in combination therewith,—although the massaging machine and operating motor units are not a part of this invention or claimed here-with.

The cabinet is preferably formed of rectangular wood sections —1—, —2— and —3—, placed in a vertical position, with the sides —1— and —2— positioned at opposite edges of the side —3— and at right angles thereto, the corner joints being made in the manner ordinarily used in cabinet making by mitering or grooving the edges together, suitable for providing a rigid structure. The base —4— is made of a rectangular wood section and preferably attached by grooved joints for adding strength and rigidity to the structure. The top —5— is also made of a rectangular wood section, preferably with beaded edges, and attached to the top edges of panels —1—, —2— and —3—, forming a rectangular box-shaped enclosure, with one open side. Around the inner corners of the closed cabinet walls are attached corner cleats —6—, —7— and —8—, securely attached to the cabinet walls for more rigidly joining the cabinet wall sections together and providing means for mortising and mounting the machine supports therein. Pivotally attached to the base —4— is a movable door panel —9—, joined to the base by the hinge —10—, fixedly attached to both base and door panel, which extends nearly the entire width of the door panel section, the door panel —9— being of a size to completely fold within the cabinet and fitting within the sides —1— and —2— and the top section —5—, folding therein in a position as one of the cabinet walls. Fixedly attached to the top —5— is a panel cleat —10a— extending the entire width of the cabinet opening, positioned to engage the door panel —9— when folded within the cabinet for retaining the same therein in a vertical position. Mounted on the outer surface at the top edge of the door panel —9— is a catch lock —11— preferably mortised within the door panel surface for presenting a neat finished appearance, and engages a catch plate —12— mortised in the adjacent face of top —5— for holding and locking the panel —9— within the cabinet when closed. The catch lock —11— is preferably made of the ring type, capable of turning the ring —13— about its pivot —14— for disengaging the lock catch, and allowing the door panel —9— to be opened. The door panel —9— when disengaged from the cabi-

net by the catch lock —11— may be unfolded on the attaching hinge —10— to a position practically parallel with the floor supporting the cabinet, as more specifically shown in Fig. 6. To the outer surface of the door panel —9— is attached floor cleats —15— and —16—, positioned crosswise of the panel section, the cleats —15— and —16— being of a different thickness to allow the door panel —9— to resume a slightly sloping position away from the cabinet, both cleats resting upon the floor surface, providing a standing platform for the person when using the massaging machine. The edges —a— and —b— of the cleats —15— and —16— are preferably beveled for neatness in appearance, while the outer surface —c— is preferably recessed and provided with rubber fillers —17— and —18— the entire length thereof for engaging the floor surfaces and preventing marring or scratching thereof when the door panel —9— is unfolded and the cabinet subject to use. Also the inside surface of the door panel —9— is completely covered with a rubber sheet matting —19— securely attached thereto, practically covering the entire inner panel face, and providing secure footing for the person standing thereon. Fixedly mounted to the inside face of the door panel —9—, near the edges —e— and —f—, are bracket pivot clips —20— attached thereto by the screws —21—. Wood brace members —22—, preferably formed of rectangular cross sections, are pivotally mounted in each of the bracket pivot clips by the pins —23— passing through the clips and brace ends, the braces —22— being free to turn thereon. The braces —22— are extended to a position of about 45 degrees with the cabinet walls when the door panel —9— is in the open position and the opposite ends engage notches —24— of the outer edges of vertical brace cleats —25—, which are fixedly attached along the inner faces of the side walls —1— and —2—. The brace cleats —25— are formed with L-shaped internal recesses —26— extending nearly the entire length thereof from the top downward and are positioned parallel to the door panel —9— when closed within the cabinet walls, but providing sufficient space between the brace cleats and door panel for allowing the brace —22— to fold therebetween. Fixedly attached to each of the upper ends of the braces —22— is an L-shaped hook plate —27—, which projects from the end of the brace and engages the L-shaped internal recesses —26— of the cleat and capable of sliding therein from the notch positions to the top end of the cabinet, and capable of assuming the various positions within said recesses as the braces —22— slide and fold thereto when closing the door panel. The notches —24— serve to engage the braces when the door is unfolded and provide rigid brace

means for the cabinet when in use, the internal recesses —26— being sufficient to allow the side movements of the L-shaped hook plate therein for lifting the braces sufficiently to disengage the notches and closing the panel within the cabinet. Across the front face of the cabinet opening, slightly above the center thereof, is mounted a wood front lateral bar —28— preferably having its outer ends mortised in the faces of the brace cleats —25— and securely attached thereto in a horizontal position. Also across the inner face of the back wall —3— is attached a rear wood lateral bar —29— mortised in the edges of the corner cleats —7—, the rear lateral bar —29— being positioned in horizontal alignment and parallel with the front lateral bar —28—, so that the upper faces of both bars are placed in the same horizontal plane. Mounted across the lateral bars —28— and —29—, at the outer ends thereof, are the cross-laterals —30—, also preferably formed of wood sections and securely attached thereto. Mounted on the top faces of the cross laterals —30— is a rectangular metal base casting —31—, formed of flanged side wall bars, having a central opening therein, and provided with bolt flanges —32— around the bottom edges for receiving the attaching bolts —33—. On the top face of the base casting —31—, adjacent to the open side of the cabinet, is formed two pivot bearings —34—. Pivotedly mounted within the bearings —34— is the base plate —35— attached thereto by the pivots —36—, the base plate —35— being capable of rotating on the pivot to either a vertical or a horizontal position, as shown in Figs. 5 and 6. The base plate —35— is formed with a flat top surface —9— for receiving and retaining the power motor —37— thereon, the motor —37— being of any standard type used to operate an attached massaging machine, the motor being connected to the base plate by means of the bolts —38—, securely attaching same thereto. The outer end of the base plate —35— is provided with an extending locking arm —39—, which projects therefrom a sufficient length to pass within slotted recesses —40— formed in the rear frame wall and engage a frame latch —41— for holding the frame in a horizontal position. The frame latch —41— is mounted on a trip bar —42—, which extends to the front cabinet opening and is supported in the notch —43— of the front lateral —28—. A coil spring —44— is attached to the trip bar —42— and connected to the back cabinet wall in a manner for turning the trip bar down and retaining the frame latch —41— to its latching position, but capable of receding within the frame recess —40—, when engaged by the end of the base plate arm —39—, allowing base plate to pass therover and lock in its horizontal position. By lifting the outer end —h— of the trip bar

—42—, the frame latch —41— may be disengaged from the base plate arm —39— and allow the base plate to be revolved to its vertical position when desired. The base plate —35— is formed with a cylindrical recess —45— positioned at right angles to the top face of the plate along the center line thereof, preferably outside the supporting pivots —26—, as illustrated in Fig. 8, the recess walls being provided with an adjusting slot and a threaded adjusting bolt —46— as a clamping means therefor. Within the recess —45— is mounted the cylindrical shaft —47— of the massaging machine bearing casting, the same being tightly clamped therein by means of the adjusting bolt —46—. The massaging machine proper is more fully and completely described in my former patent heretofore mentioned, and comprises the bearing casting —47— supporting a rotatably mounted horizontal crank shaft —48— and attached crank wheels —49— securely attached to the shaft. Also pivotally mounted on the bearing casting —47—, concentric with the crank shaft —48— is a swinging bearing frame —50— which carries applicator arms —51— pivotally mounted at the outer ends thereof, each applicator arms —51— being connected to one of the crank wheels —49— by pitman arms —52— also pivotally connected to the applicator arms and crank wheels, the applicator arms —51— being provided with a series of applicator buttons —53— positioned at uniform spaces along the outer faces thereof and carry a detachable applicator belt —54— thereon, the crank shaft —48— and wheels —49— being rotated by a connecting belt —55— leading direct to the motor drive pulleys —56— and is driven thereby by the electric current communicated to the motor through the double terminal wires —58— passing through the switch —59— in the bearing casting —47— communicated directly to the motor through the circuit wires —60—. The operation of the massaging machine is fully explained in my former patent above mentioned, the design being capable of rotating the operating frame —50— to any position about the pivoted bearing and also adjust the connected applicator arms and pitman arms accordingly, and which adjustment is essential, as shown in Fig. 5, when the pivot base plate and the attached machine is turned to the vertical position and folded for allowing the closing of the door panel —9— within the cabinet.

It is apparent that my cabinet is subject to various modifications in both the general design and mechanical details, and that various types and designs of base plates would be necessary for receiving and retaining different types of massaging machines thereon, and various locking means may be devised for retaining the base plate in the different

positions, and I claim as my invention the designs as shown and any other design which would be practically a substitution of the parts herein described.

5 Having fully described my massaging machine cabinet, what I claim as my invention and desire to secure by Letters Patent is:

1. A portable cabinet adapted for supporting and enclosing a massaging machine, comprising a rigid cabinet enclosure, formed with one open side, a panel door pivotally mounted within said side opening, a support member pivotally mounted within the cabinet enclosure designed to receive and support 10 a massaging machine thereon, said support member being capable of being rotated from a horizontal to a vertical position about its pivot support within the cabinet enclosure, and means mounted within the cabinet for 15 rigidly retaining the pivoted support member and attached massaging machine in its extreme pre-determined positions therein.

2. A portable cabinet adapted for supporting and enclosing a massaging machine, comprising a rigid rectangular box-shaped cabinet enclosure, formed with one open side, a panel door pivotally mounted within the said cabinet side opening and designed to turn about its supporting pivot to a position 20 parallel to the supporting floor, attached braces for rigidly connecting the panel door to the cabinet walls when in its open position, a support member pivotally mounted within the cabinet enclosure capable of being rotated from a horizontal to a vertical position 25 within the cabinet, means mounted thereon for rigidly retaining the support member in its extreme pre-determined positions within the cabinet, said support member being capable of receiving and supporting an attached massaging machine thereon in a manner for folding and unfolding the same within the cabinet enclosure.

3. A portable cabinet adapted for supporting and enclosing a massaging machine, comprising a rigid rectangular box-shaped enclosure, formed with one open side, a panel door pivotally mounted at the base of said cabinet capable of folding within the cabinet 30 side opening completely closing the same, means attached to said panel door for locking the same within the cabinet side opening, brace means pivotally attached to the panel door for rigidly connecting the said panel door to the cabinet walls when the door is unfolded to a position parallel with the supporting floor, a supporting frame fixedly mounted within the cabinet enclosure positioned therein in approximately a horizontal 35 plane, a movable support member pivotally mounted on the said support frame capable of being rotated from a horizontal to a vertical position about the supporting pivot within the cabinet, means mounted within the cabinet for engaging and retaining the said piv-

oted support member in its extreme pre-determined positions within the cabinet, said pivoted member being designed to receive and support an attached massaging machine thereon in a manner for rotating the same about the supporting pivot for folding and unfolding the said massaging machine in and out of the cabinet enclosure.

4. A portable cabinet adapted for supporting and enclosing a massaging machine therein, comprising a rigid rectangular box-shaped enclosure, formed with one open side, a panel door fitted within said side opening and completely filling same and attached to the said cabinet base by hinge means, said panel door being capable of unfolding and resting upon the supporting floor, locking means mounted thereon for engaging and locking said panel door within the cabinet wall opening, brace means pivotally attached to said panel door and connected to the cabinet walls in a manner for rigidly bracing the same when the panel door is in its open position, a support frame fixedly mounted within the said cabinet enclosure positioned in a horizontal plane, an adjustable support member pivotally mounted on the support frame capable of being turned from a horizontal to a vertical position therein, means mounted on the said support frame for rigidly holding the pivoted support member in its extreme pre-determined positions therein, the said pivoted support member being designed for retaining a massaging machine fixedly attached thereto in a manner for rotating the said massaging machine from a horizontal operating position to a vertical position within the cabinet enclosure sufficiently for allowing the cabinet door to be folded within the cabinet opening.

5. A portable cabinet adapted for supporting and retaining a massaging machine therein, comprising a rigid rectangular box-shaped cabinet enclosure, formed with one open side, a panel door fitted within said side opening and attached to the cabinet base by hinge means along the bottom edge of said panel capable of unfolding to a position resting upon the supporting floor, means mounted thereon for engaging and locking said panel door within the cabinet side opening, brace means pivotally mounted on the said panel door and slidably connected to the cabinet side walls in a manner for forming rigid bracing to the cabinet when the cabinet door is in its open position, horizontal lateral supports fixedly attached to the cabinet walls, a rigid support frame fixedly mounted on said horizontal lateral supports, an adjustable support member pivotally mounted on the support frame along the front edge thereof capable of being rotated from a horizontal to a vertical position within the cabinet, a locking latch pivotally mounted on the said support frame along the back edge thereof positioned to engage and support the pivoted sup-
